Wis., a corporation of Wisconsin

Application March 13, 1944, Serial No. 526,199

9 Claims. (Cl. 92—44)

1

This invention relates to suction pick-off roll assemblies and press sections for paper making machines.

Specifically the invention deals with paper making machine press sections wherein the paper web advancing through the press section from the forming section to the drier section never has the direction of travel changed unless it is disposed between a pair of felts, or subjected to suction. The press sections of this invention include cooperating suction transfer rolls and press rolls wherein one roll of a cooperating pair receives the sheet and subjects it to low vacuum to hold it thereon for conveying it to a transfer point, thereby eliminating any chance for the sheet to fly off the roll when traveling at high speed.

It has heretofore been necessary to use singed pick-up felts in drier sections in order to keep the sheet on the felt especially as it passes through a top pick-off roll assembly in being transferred from the forming section to the press section of the machine. Such singed pick-up felts have also been necessary in suction presses since the felts are usually separated or divided after the first suction press. Now, the singed type of pick-up felt is very heavy and resists water removal as it is quite dense, and air and water will not readily pass through it.

The present invention makes possible the use of very open, porous felts for conveying wet fibrous webs from their forming surfaces through the press section to the drier section of a paper machine. In accordance with this invention the paper web is never permitted to turn around a roll, and never has its direction of movement changed, unless it is held on its carrier felt by means of vacuum or is between a pair of carrier felts. The present invention simplifies felt runs in press roll sections for paper making machines and especially Yankee-type paper making machines.

A feature of the invention involves the elimination of the heretofore encountered problem of having the sheet stick to the wrong felt after leaving a suction press. In accordance with this invention, a felt conveying the web to a suction press has the web covered with a cooperating felt in advance of the press, and suction in advance of the nip of the press transfers the web from the carrying felt to the covering felt. Then, as the pair of felts with the web therebetween pass through the nip of the press, the web is retransferred back to the first felt and held thereon by suction applied through the first felt after the nip area. This eliminates the heretofore encountered difficulties in having the web stick to the covering

2

felt. As a result of this feature of the invention, press sections can be operated more efficiently and at higher pressures.

A further feature of the invention is the provision of transfer roll assemblies with high vacuum and low vacuum areas wherein the low vacuum areas will hold the sheet on a roll feeding it to a transfer point and will remove some water from the sheet while so holding it, and wherein the high vacuum areas will dry the sheet, and hold water in the holes of the roll until the sheet is removed out of the path of water discharged from said holes.

An object of the invention is therefore to provide press sections for paper making machines capable of handling paper at high speeds without the use of singed pick-up felts to convey the paper.

Another object of the invention is the provision of paper machine press sections with felt runs and suction rolls so arranged that the direction of the paper is not changed through its entire passage between the forming section and the drier section of the machine unless the paper is disposed between a pair of felts, or is held on a felt by suction applied through the felt.

A still further object of the invention is to eliminate the possibility of separation of a web of paper from the carrier felt as the felt and paper turn around a roll by subjecting the paper to vacuum during the entire time it is changing direction of travel.

A still further object of the invention is to provide a transfer roll assembly having a suction couch roll cooperating with a suction transfer roll and a final couch roll or turning roll for directing the forming wire off of the couch roll at the nip between the couch roll and transfer roll.

A still further object of the invention is to provide a press section for a Yankee-type Fourdrinier paper making machine wherein suction transfer rolls and suction press rolls cooperate with open readily drained felts to convey the paper through the section without encountering undesired separation of the paper from the felt, irrespective of the speed of operation.

A still further object of the invention is to provide a Yankee-type Fourdrinier paper making machine with a drier section including a predrier drum in advance of the main drier drum and suction rolls cooperating with felts to continuously support the paper web from the forming section to the main drier drum.

Other and further objects of the invention will be apparent to those skilled in the art from the following detailed description of the annexed

sheets of drawings which, by way of preferred examples only, illustrate two embodiments of the invention.

On the drawings:

Figure 1 is a fragmentary somewhat diagrammatic side elevational view of the press and drier sections of a Yankee type Fourdrinier paper making machine embodying transfer and press roll assemblies and felt runs in accordance with this invention.

Figure 2 is an enlarged side elevational view, with parts broken away and shown in vertical cross section, of the transfer roll assembly of Figure 1.

Figure 3 is an enlarged fragmentary side elevational view, with parts broken away and shown in vertical cross section, of another transfer roll assembly of Figure 1.

Figure 4 is a somewhat diagrammatic side elevational view of a press and drier section of a Yankee-type Fourdrinier paper making machine equipped with transfer rolls, suction presses, and felt runs in accordance with a modified embodiment of the invention.

As shown on the drawings:

In Figure 1 the reference characters F designate a floor section of a paper mill supported on columns C above a basement floor, for example, and carrying posts P supporting overhead beams such as B.

Supports for a transfer roll assembly 10, a first horizontal press roll assembly 11, a second vertical press roll assembly 12, a predrier drum assembly, 13, a stripper roll assembly 14, a second transfer roll assembly 15, and the first drier drum 16 of a drier section are carried on the floor F. A support for the Yankee drier drum 17 is mounted on the beams such as B.

As shown in Figures 1 and 2, the transfer roll assembly 10 includes a suction couch roll 18 and a plain couch or turning roll 19 within the loop of the paper machine forming wire 20 together with a suction transfer roll 21 and a plain guide roll 22 within the loop of a pick-up felt 23.

The suction transfer roll 21 is pivotally mounted on the floor F as at 24 and a pressure-applying jack 25 coacting with the adjacent post P maintains the transfer roll in cooperating relation with the couch roll to define a transfer nip N therebetween.

The forming wire 20 is wrapped around the top of the suction couch roll 18 and travels downwardly under the plain couch roll or turning roll 19 to convey the web of paper W thereon through the nip N of the assembly onto the pick-up felt 23 which is guided into the nip N by a guide roll 26 positioned outside the loop thereof and which is guided out of the nip by the roll 22 inside of the loop thereof.

The suction couch roll 18 has a suction gland or box 27 therein with packing strips 28, 29, and 30 projecting therefrom into sealing relation with the perforated shell 32 of the roll. The shell 32, of course, is rotatable around the stationary suction box 27, and the packing strips 28 and 29 are positioned to extend around the downturned side of the roll to define a suction area a serving to hold the wire 20 and web W tightly against the shell 32 even though the wire and web are traveling at high speed. A butterfly-type valve 33 controls the extent of communication between the suction area a and the interior of the suction box 27 so as to regulate the degree of suction in the area a. This suction area a is generally maintained under a relatively low vacuum and

its function is to hold the sheet W on the roll and to remove some water from the sheet. The spaced packing strips 28 and 30 define a suction area b in full communication with the interior of the suction box 27, and this suction area extends from the area a into the nip N. The function of the suction area b is to remove water from the web W and to prevent the water in the holes of the shell 32 from being discharged back through the wire into the web.

The transfer roll 21 has a stationary suction box or gland 34 therein with a perforated metal shell 35 rotatable therearound and covered with a similarly perforated rubber cover 36. The suction box has spaced packing strips 37 and 38 defining therebetween a suction area c in full communication with the interior of the suction box 34 and extending from the nip N into spaced relation beneath the nip.

The turning roll or plain couch roll 19 wraps the forming wire 20 partially around the transfer roll 21 to guide the wire off of the roll 18 at the point where the holes in the roll shell 32 are passing over the packing strip 30 so that the wire and web W thereon is out of the path of streams of water S discharged from holes in the shell when the vacuum in the holes is released. It will be noted from Figure 2 that nip N terminates at the packing strip 30 so that the wire is not removed from the shell 32 when the holes in the shell are in communication with the suction area b. As a result of this arrangement high vacuum can be maintained in the suction area b. The streams of water S are collected in a pan or trough 39 surrounding the roll 18.

The pick-up felt 23 is wrapped around the rubber cover 36 of the transfer roll 21 and covers the suction area c to receive the web W from the wire 20 as the web passes through the nip. It will be noted that the suction area c extends for a distance beneath the nip to subject the pick-up felt and web to suction for insuring complete transfer of the web off of the wire onto the pick-up felt as well as to prevent the web from flying outwardly back toward the wire. The pick-up felt with the web thereon passes tangentially off of the roll and travels in a straight path to the guide roll 22. A guide roll 40 adjacent the roll 22 directs a bottom felt 41 against the web W on the pick-up felt 23 before the web and felt turn under the roll 22. Therefore as soon as the direction of travel of the web W is changed, the web is covered by the felt 41 and cannot fly off of the felt 23.

As shown in Figure 1, the web W between the pick-up felt 23 and covering felt 41 passes from the roll 22 to the first horizontal suction press assembly around the top of the suction roll 42 thereof, thence downwardly through the nip between this roll 42 and the cooperating roll 43.

The roll 42 has a first low vacuum suction area 42a extending from the top thereof to a high vacuum area 42b extending through the nip of the rolls. A valve 42c is provided to regulate the vacuum in the area 42a as compared with the high vacuum in the area 42b. The roll 43 has a suction area 43a in the nip and a low vacuum suction area 43b extending around the bottom 75 part of the roll from the area 43a and having the vacuum therein controlled by a valve 43c.

As the web between the felts 23 and 41 passes through the nip of the horizontal press, it is subjected to vacuum from both high suction areas 42b and 43a so that water will be sucked through

both felts out of both faces of the web. The felt 41 is separated from the web after passage through the nip, but the suction area 43b will hold the web tightly on the felt 23 as it passes under the roll 43. The felt 41 then travels away from the web around guide rolls 44 and between wringer rolls 45 back to the roll 40.

The transfer roll 21, like the couch roll 18, is equipped with a trough 46 collecting streams of water S spewing from the holes in the rubber cover 36 and shell 35 after vacuum in the holes is released, but it will be noted that the roll 22 guides the web and felt out of the path of these streams S.

The roll 42 of the press 11 likewise has a trough 47 collecting water from the holes in the roll shell. A collecting pan or trough 48 is provided for the roll 43 of this press.

The felt 23 with the web W is covered with a second bottom felt 49 as soon as it leaves the suction area 43b of the roll 43 and passes between the felts 23 and 49 through the nip of the vertical press 11 between the rolls 50 and 51 of this press. The roll 50 is a suction roll and has a high vacuum suction area 50a at the nip together with a lower vacuum suction area 50b controlled by a valve 50c extending from the vacuum area 50a around the top turning portion of the roll. The roll 51 can be a plain or rubber-covered roll, and is carried on a pivotal support 51a from the adjacent post P and is urged by a jack 52 suspended from the beam B with a desired amount of pressure against the roll 50. The web W is transferred off of the pick-up felt 23 as it passes through the nip of the vertical press and suction in the suction areas 50a and 50b holds the web on felt 49. The felt 23 passes upwardly around the top roll 51 over a guide roll 53 and thence under a guide roll 54 and upwardly between wringer rolls 55. A shield 56 is provided to define a trough under the roll 54 so that water squeezed out of the felt by the wringers 55 will not re-wet the felt or web. The felt next travels over a guide roll 56, thence around a guide roll 57 to a tension roll 58 and next from the tension roll 58 around a guide roll 59 back to the directing roll 26.

The felt 49 conveys the web around the roll 50 to the predrier 13 and contacts the web with the drum 60 of this predrier. The felt causes the web to be held in tight engagement around the periphery of the drum where it will be dried by the heat of the drum. The felt 49 is then trained around the roll 61 of the stripper 14. This roll 61 has a high vacuum suction area 61a extracting water from the web and pulling the web off of the drum 60 to cause it to hug the felt 49. A low vacuum suction area 61b controlled by a valve 61c is provided to cause the web to remain on the felt as it passes around the roll 61. These high and low vacuum areas may be constructed in a manner similar to that shown in Figs. 2 and 3. A covering felt 62 is directed over the roll 61 to cover the web thereon by means of a directing roll 63. The web passes between the felts 49 and 62 to the under side of the roll 64 of the transfer 18. This roll 64, as best shown in Figure 3, includes a perforated rotatable metal shell 65 covered with a similarly perforated rubber cover 66. A suction gland 67 in the roll 66 has openings and packing strips associated therewith defining a high vacuum suction area d, a low vacuum suction area e and a second high vacuum suction area f. The low vacuum suction area e is controlled by means of a valve 68. The

felt 49 is separated from the web W and the web is transferred onto the covering felt 62 by the suction area d. A guide roll 69 directs the felt 49 away from the roll 64 and the felt then passes over guide rolls 70 to a tension roll 71 and around rolls 72 back to the roll 73 which directs it into recontact with another portion of the web at the suction roll 43.

The suction area e of the roll 64 holds the web W on the felt 62 as it travels around the roll, and the suction area f of this roll extracts an additional amount of water from the web in advance of the nip provided by the roll and the drum 74 of the cooperating Yankee 11. The nip is at the terminal end of the suction area f so the web is transferred to the drum 74. Any water released from holes in the shell 65 and its rubber cover 66 is caught in a trough 75. The felt 62 passes over the top of the roll 64 and under a guide roll 76 having a shield 77 therearound. The felt then passes upwardly between wringer rolls 78, and any water squeezed out of the felt will be collected in the shield 77. This shield 77 can cooperate with the trough 75 to discharge its water into the trough. Guide rolls 79 and tension roll 80 guide the felt back to the directing roll 63 over the top of the stripper roll 61.

The paper is conveyed around the drum 74 and is removed from the drum by means of a doctor 81. Rolls 82 then guide the paper, which may be creped, to the first drier 83 of the drier section 16. A felt 84 can be provided to hold the paper on the drum 83.

It will be noted that the entire passage of the paper from the forming wire 20 to the Yankee drier 74 is accomplished without changing the direction of travel of the paper unless it is held on a felt by means of suction, or disposed between two felts. This prevents any possible separation of the paper from a carrier felt and the section can be run at very high speed without injury to even a very light weight delicate web such as tissue.

A Jack 85 is provided on the floor F cooperating with a pivoted trunnion lever 86 which is pivoted on a post P as shown to support the roll 64 of the transfer device 18. The jack 85 can be operated so that the transfer roll 64 will have the desired nip pressure with the Yankee drum 74.

In the embodiment shown in Figure 4, parts identical with parts described in Figures 1 to 3 have been marked with the same reference numeral. It will be noted from Figure 4 that the couch roll 18 does not have nip pressure with the cooperating transfer roll 21 since it is spaced from the transfer roll but the turning roll 19 guides the forming wire 20 so as to wrap the transfer roll 21 over the suction area c thereof. The suction area c can then transfer the web from the wire 20 to the pick-up felt 23. This pick-up felt cooperates with the bottom felt 41 as described hereinabove to convey the web between felts to a first press 12 which has vertical press rolls 50 and 51 with a suction area 50a in the roll 50.

The felt 41 and the top felt 23 then convey the web from this first press 12 directly to the transfer assembly 15 where the web is transferred to the Yankee drier 74. In this arrangement the horizontal press assembly 11 and the predrier 13 are omitted and instead the felts 23 and 41 convey the web therebetween direct from the transfer assembly 10 to a vertical press 12 and the transfer assembly 15. The arrangement of Figure 4, like the arrangement of Figure 1, does not permit the direction of travel of the web to

change from the time it leaves the forming wire 20 until it reaches the drum of the Yankee drier 17 unless the web is either held on a felt by suction, or disposed between two felts.

The suction transfer assemblies and press rolls of this invention having the low vacuum suction areas cooperating with high vacuum suction areas make possible the holding of an uncovered web on a felt as it passes around a roll even at the highest speeds without permitting the web to leave the felt and without necessity for slowing up the assembly. The arrangement also makes possible the use of lighter, more open, and less dense felts in place of the heretofore necessary singed pick-up felts. The open felts are readily drained and suction capacity for pulling water and air through them is much less than when the denser singed felts are used. As a result, the low vacuum areas which hold the web on the felt and effect a better transfer than the heretofore used singed pick-up felts, do not increase the suction requirements above those requirements heretofore necessary with the singed felts.

It will, of course, be understood that various details of construction may be varied through a wide range without departing from the principles of this invention and it is, therefore, not the purpose to limit the patent granted hereon otherwise than necessitated by the scope of the appended claims.

We claim as our invention:

1. In a paper making machine, a looped forming wire having an upper run, a couch roll in the loop of the wire at the end of said run, a turning roll in the loop of the wire below said couch roll receiving the wire from the couch roll, a looped pick-up felt, a transfer roll in the loop of said pick-up felt projecting into the run of the forming wire between the couch roll and turning roll for wrapping the pick-up felt, the forming wire, and any web on the forming wire around a portion of the transfer roll, said couch roll having a low vacuum area extending around that portion of the roll covered by the wire as it turns from its horizontal run to travel toward the turning roll together with a high vacuum area following the low vacuum area, said turning roll separating the forming wire from the couch roll as the wire leaves the high vacuum area of the couch roll, said transfer roll having a vacuum area in the portion thereof covered by the pick-up felt and wire effective to transfer the web to the pick-up felt after the web has passed the high vacuum area of the couch roll, a directing roll in the loop of the pick-up felt receiving the felt from the transfer roll around the under side thereof and providing a straight run of felts between the transfer roll and the directing roll, a bottom felt covering the web on the pick-up felt before its straight run direction is changed and cooperating with the pick-up felt to convey the web therebetween, a suction press receiving the felts and web therethrough, a second directing roll separating the felts and uncovering the web, a drier drum, a suction roll adjacent the drier drum receiving the uncovered web therearound, and said suction roll having a pair of spaced high vacuum areas positioned to act on the web as it comes onto the roll and as it leaves the roll to be transferred to the drier drum together with an intermediate low vacuum area between said high vacuum areas holding the web on the roll, said web in its entire travel from the forming wire to the drying drum being between felts or

under the influence of vacuum whenever it would have a tendency to leave the felt.

2. In a paper making machine, a looped forming wire having an upper run, a couch roll in the loop of the wire at the end of said run, a turning roll in the loop of the wire below the couch roll receiving the wire from the couch roll, a looped pick-up felt, a transfer roll in the loop of said felt, a directing roll in the loop of said felt below the transfer roll, said transfer roll receiving a portion of the forming wire and any web thereon therearound in the run of the wire between the couch roll and the turning roll, said directing roll separating the pick-up felt from the wire, said couch roll having a vacuum area therein holding the web on the forming wire as it travels around the roll and also having a second vacuum area following said first mentioned area to extract water through the wire from the web, said transfer roll having a suction area receiving the web from the last mentioned suction area of the couch roll to transfer the web to the pick-up felt, a covering felt trained around the directing roll in the loop of the pick-up felt for covering the web thereon at the end of said straight run of said felt, a horizontal suction press having a roll receiving the felts with the web therebetween therearound, said roll having a low vacuum suction area causing the felts and web to closely hug the roll, said suction press having a suction nip with opposed vacuum areas for drawing water through both felts from the web, a roll separating said bottom felt from said web, the second roll of the horizontal press having a low vacuum area therein holding the uncovered web on the pick-up felt as it travels under the roll, a second covering felt, a vertical suction press receiving the second covering felt and pick-up felt with the web between the felts from the second roll of the horizontal press, the top roll of said vertical press receiving the pick-up felt therearound, said bottom roll of the vertical press having a suction area in the nip of the press and a second suction area beyond said nip holding the web on the second covering felt as it passes around the roll, a drier drum receiving the web on the second covering felt from said bottom roll of the vertical press, a stripper roll adjacent the drier drum having a suction area for holding the web on the covering felt as it passes around the stripper roll, a top felt cooperating with the stripper roll to cover the web on the second bottom felt, a transfer roll in the loop of said top felt having a first suction area for transferring the web from the second bottom felt to the top felt together with a second vacuum area holding the web on the top felt as it travels around the roll, and a drier drum receiving the web from said roll, said web in its entire travel from said forming wire to said last mentioned drier drum being held under the influence of vacuum or disposed between felts whenever it would have a tendency to leave the felt.

3. In a paper making machine, a looped forming wire having an upper run, a couch roll in the loop of the wire at the end of said run, a turning roll in the loop of the wire below the couch roll receiving the wire from the couch roll, a looped pick-up felt, a transfer roll in the loop of the felt, a directing roll in the loop of the felt, said transfer roll and directing roll holding the pick-up felt against the forming wire and any web thereon in the run of the wire between the couch roll and the turning roll, said couch roll having a vacuum area holding the web on the

wire as it passes around the roll, said transfer roll having a vacuum area transferring the web from the wire to the pick-up felt, said turning roll separating the wire from the transferred web, a bottom covering felt, a roll in the loop of the covering felt wrapping the same around the web as it passes under the directing roll to cooperate with the pick-up felt for conveying the web therebetween, a suction press receiving the felts with the web therebetween, a second transfer roll in the loop of the pick-up felt receiving the felts and web from the suction press, a second roll in the loop of the bottom felt separating the bottom felt from the web said second transfer roll having a suction area for transferring the web to the pick-up felt and holding the web on the pick-up felt as it travels around the roll, and a drier drum cooperating with the second transfer roll to receive the web therefrom, said web in its entire travel from the upper run of the forming wire to the drier drum being under the influence of vacuum or between felts whenever it would have a tendency to leave the felt.

4. In a paper making machine including a looped forming wire and a drier drum in spaced relation therefrom, a suction press section between the forming wire and the drier drum including a looped relatively open lightweight pick-up felt, a suction transfer roll in the loop of the felt picking up the web from the forming wire, a pair of rolls arranged for extending between them the wire while carrying the web to wrap it partially around the suction area of said transfer roll, a bottom covering felt cooperating with the pick-up felt to cover the web, the suction press receiving therethrough the felts with the web therebetween, a roll in the loop of the covering felts separating said felts to uncover the web, one of the rolls of said suction press having a vacuum area holding the pick-up felt and uncovered web thereon on the roll as it travels therearound, a second bottom felt covering the web on the pick-up felt as it leaves the suction press, a second suction press receiving therethrough the felts with the web therebetween, said pick-up felt following one of the rolls of said second suction press and said second covering felt following the other of the rolls of said suction press, said other roll having a vacuum area holding the web on the second bottom felt, and a drier drum receiving the web from said other roll of the second suction press, said web in its entire travel from the forming wire to the drier drum being under the influence of vacuum or disposed between felts whenever its direction of travel is changing, or whenever it tends to leave the felt.

5. A suction transfer roll assembly comprising a suction couch roll, a forming wire trained around the couch roll, a turning roll receiving the forming wire therearound from the couch roll, said couch roll having a low vacuum area for holding a web of paper on the forming wire as it travels around the couch roll, said couch roll also having a high vacuum area adjacent the low vacuum area to extract water from the web, a cooperating suction transfer roll, said turning roll separating said wire from said couch roll at the end of said high vacuum area, a pick-up felt trained around said cooperating suction roll, a directing roll within the loop of the pick-up felt, said directing roll cooperating with said turning roll to separate the pick-up felt and the forming wire, and said suction transfer roll having a suction area covered by said pick-up felt for

transferring the web from the wire to the pick-up felt.

6. A suction transfer roll assembly comprising a pair of cooperating suction rolls, a forming wire and means training said wire around one of said suction rolls with its web carrying surface facing outwardly and thereafter partially wrapping the wire around the other roll with its web carrying surface facing said other roll following the nip of said rolls, a pick-up felt trained around said other of said suction rolls, the first said suction roll receiving the forming wire therearound having a low vacuum suction area to hold the web on the wire as it travels around the roll and having a smaller high vacuum suction area immediately following the low vacuum area to extract water from the web on the wire, said other suction roll receiving the pick-up felt therearound projecting into the path of the forming wire and web as it leaves the high vacuum area of said first roll, and a vacuum area in said second roll following the nip of the rollers acting through the pick-up felt to draw the web from the wire onto the pick-up felt.

7. In a paper making machine, a looped forming wire, a suction couch roll within the loop of the wire, a turning roll within the loop of the wire, said couch roll receiving the wire thereover and said turning roll receiving the wire thereunder from said couch roll, a stationary suction box in said couch roll having a first suction area of appreciable width holding a web on the forming wire as it turns around the roll together with a second and narrower suction area immediately following said first suction area, a valve cooperating with said suction box to maintain the first suction area at lower vacuum than the second suction area, said turning roll directing the wire off of said shell after the holes in the shell have passed beyond the second suction area but before the said holes have had the vacuum therein released, and a collecting device interposed between the couch roll and the turning roll receiving water spewed from the holes in the shell of the couch roll when the vacuum is released.

8. In combination, first and second suction rolls defining a nip therebetween, a forming wire trained around said first suction roll through said nip, means for wrapping said forming wire partially around said second suction roll beyond the nip, a felt for covering the paper web on said wire as it passes through said nip, means guiding said felt to lap it around said suction roll beyond said nip, a suction box in said first suction roll positioned to impose suction on the first roll preceding the nip and slightly beyond the nip, and a suction box in said second roll positioned to suck water through the felt beyond the nip for effecting transfer of the paper sheet from the wire to the felt.

9. In combination, first and second suction rolls defining a nip therebetween, a forming wire trained around said first suction roll through said nip, means for wrapping said forming wire partially around said second suction roll beyond the nip, a felt for covering the paper web on said wire as it passes through said nip, means guiding said felt to lap it around said suction roll beyond said nip, a suction box in said first suction roll having an offgoing seal so arranged relative to said nip that water sucked into the holes of the first suction roll will be thrown clear of the wire on the leaving side of the nip, and a suction box in said second roll positioned to suck water through the felt beyond the nip for ef-

11

fecting transfer of the paper sheet from the wire to the felt.
